UNITED STATES PATENT OFFICE.

GEORGE W. GOSS, CHARLES E. GOSS, AND CHARLES O. ROSHON, OF BALTIMORE, OHIO.

FUEL TANK.

Application filed July 15, 1920. Serial No. 396,580.

To all whom it may concern:

Be it known that we, GEORGE W. GOSS, CHARLES E. GOSS, and CHARLES O. ROSHON, citizens of the United States, residing at 5 Baltimore, in the county of Fairfield and State of Ohio, have invented certain new and useful Improvements in Fuel Tanks, of which the following is a specification.

This invention relates to improvements 10 in the fuel tanks of motor driven vehicles and has for its primary object to provide a fuel tank wherein is provided main and emergency tanks, the emergency tank being removably positioned within the main tank 15 and so located with respect to the filling opening of the tank that fuel will first fill the emergency tank before gaining access to the main tank, a construction being therefore provided which enables the tank structure to carry at all times a reserve amount 20 of fuel, which may be used for emergency purposes when the contents of the main tank have been fully drawn off, either through accidental, negligence or other causes.

For a further understanding of the invention, reference is to be had to the following description and to the accompanying drawing, in which similar characters of 25 reference denote like and corresponding parts throughout the several views thereof.

In said drawing:

Figure 1 is a vertical sectional view taken 30 through the improved fuel tank structure comprising the preferred form of the present invention.

Figure 2 is a top plan view thereof, and, 35

Figure 3 is a detailed perspective view of the emergency tank.

Referring more particularly to the form 40 of the invention disclosed in the accompanying drawing, the numeral 1 designates the improved tank structure comprising the present invention in its entirety. This tank structure is formed to comprise a main 45 outer tank 2, which may be formed from any suitable materials and of any desired proportion, as will be clearly understood. The upper portion of the tank 2 is provided with an opening 3, in which is inserted and 50 suitably secured a ring or collar 4, which latter serves to reinforce the edges of the opening 3 and to render the construction of the tank 2 at portions surrounding the opening 3 of substantial and strong construction.

Threaded into the collar 4 as at 5 is a

metallic plate member 6, which has its upper surface arranged to terminate substantially evenly with the upper surface of the collar 4, and furthermore, said plate member is provided with a plurality of fingers 7, by means of which its threaded rotation into and out of the collar 4 is facilitated. In this instance, the plate member is provided to one side thereof with a threaded opening 8, in which is removably received a similarly threaded filling cap or plug 9, which is adapted to normally cover the fuel entrance of the tank structure. The under side of the plate member 6 is provided with a flange 10, to which is suitably secured the upper annular edge 11 of an emergency tank 12.

This tank may be of any suitable size and construction and is of such proportion as to be capable of being withdrawn from the tank 2 by way of the opening 3 provided in the latter. It will be observed that the tank 12 is situated in depending relationship with respect to the plate member 6, and by being connected with the latter said emergency tank will normally occupy a suspended position within the tank 2. Moreover, the tank 12 is provided with an open upper end which is adapted to be situated immediately beneath the filling opening 8, so that fuel to be placed within the tank 2 must first be received within the emergency tank, a feature which insures the required reserve amount of fuel within the tank 12 in a manner independent substantially of the main tank. The upper edge 11 of the emergency tank is provided with an opening or recess 13, which is so situated that when the tank 12 has been filled, fluid placed therein will overflow by way of the opening 13 and will then be discharged into the main tank, permitting of the filling of the latter.

In operation, fuel is withdrawn from the main tank by way of the usual outlet connection 14 provided in the base of the tank and should it happen during the operation of an associated vehicle, that the contents of the main tank should become exhausted either by virtue of forgetfulness or other accidental reasons, the supply of fuel may be replenished by the fuel within the emergency tank. Use of this latter fuel may be brought about by removing the plate member 6 and its associated emergency tank from their applied positions in connection

with the collar 4. When so removed, the emergency tank is positioned immediately above the opening 3 and is inverted so that its contents may drain out of the opening 13 and deposited within the main tank, thus permitting the fuel to be utilized in the ordinary manner. After the fuel has been drained from the emergency tank, the latter together with its plate member 6 are again positioned in engagement with the collar 4, and the vehicle may then continue until the tank 2 is again replenished with fuel. It will be understood that the emergency tank may be of any desired proportion, but the same should receive a sufficient amount of fuel to operate the motor of the vehicle for a considerable period of time. It will be observed that by reason of the location of the reserve or emergency tank, it will be impossible to fill the main tank without first filling said reserve tank. This provides a feature which insures the complete filling of the tank 12 in a substantially automatic manner and without involving the necessity of relying upon the memory of the vehicle operator. If desired, the lower edge of the opening 13 may be provided with an inwardly directed flange 15, which serves to confine the contents of the tank 12, and prevents the fuel of the latter from being jostled out of the opening 13 during the operation of the vehicle. Also, one side of the tank 12 is preferably indented as at 16, which indented portion is adapted to register with one side of the filling opening 8, whereby upon the removal of the cap 9, a gage stick or the like may be inserted into the main tank for the purpose of denoting the fuel level of the latter. The level of the fuel in the main tank may therefore be denoted by the mere removal of the cap 9, a feature which does away with the necessity of removing the plate member 6 and the associated reserve tank for mere fuel level determining purposes.

In view of the foregoing description, taken in connection with the accompanying drawing, it will be manifest that the invention provides a simple and useful structure of a substantially automatic nature which will overcome the annoyance and inconvenience due to accidental exhaustion of the contents of a fuel tank. The location of the emergency tank is such that the reserve supply of fuel may be readily obtained, which will be sufficient under ordinary circumstances to supply the needs of an associated motor until the main tank may again be fully replenished. The invention is also

capable of being applied to fuel tanks of standardized construction now found upon many makes of motor vehicles, and by being in the nature of an attachment, it is obvious that the same does not necessitate tanks especially designed for the reception of the emergency tank. This is a feature which considerably reduces the cost of manufacture and installation of the invention.

It is not claimed that the present invention broadly covers the idea of providing an emergency fuel tank within a main fuel tank, but that said invention is defined and the scope thereof indicated by the following claims.

What is claimed is:

1. In a fuel tank for motor vehicles, the combination with a main tank having an opening formed therein, of a plate member removably fitted within said opening, an emergency tank secured to and situated to depend from the under side of said member and to extend within said main tank, said emergency tank having its upper portion formed with an opening establishing communication between said tanks, and an inwardly directed flange projecting from the inner wall of said emergency tank at a position contiguous to the opening in the latter.

2. In a fuel tank for motor vehicles, the combination with a main tank having a reinforced opening formed therein, of a plate member removably fitted within said opening, a filling cap threaded into an opening provided in said plate member, an emergency tank secured to and depending from said plate member and located immediately beneath the opening provided in the latter, said emergency tank having its upper portion provided with an opening establishing communication between said tanks, and one side of said emergency tank being situated substantially in registration with the opening provided in said plate member to permit a gage member to be inserted into said main tank by the removal of said filling cap.

3. In combination with a main fuel tank, an emergency tank depending into the fuel tank, single means for filling both tanks, the emergency tank having means in registry with the filling means to permit a gage member to be inserted in the main tank.

In testimony whereof we affix our signatures.

GEORGE W. GOSS.
CHARLES E. GOSS.
CHARLES O. ROSHON.
